UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

No. 823,664.

Specification of Letters Patent.

Patented June 19, 1906.

Application filed June 13, 1903. Serial No. 161,339.

To all whom it may concern:

Be it known that I, MATTHIAS BROCK, a citizen of the United States, residing at Boston, in the county of Suffolk and Commonwealth of Massachusetts, have invented certain Improvements in Lasting-Machines, of which the following description, in connection with the accompanying drawings, is a specification, like reference characters on the drawings indicating like parts in the several figures.

This invention relates to lasting-machines of the type known as the "McKay and Cope-land" lasting-machine, and particularly to the mechanism employed in that machine for lasting the sides of the shoe. The side-lasting mechanism of said machine comprises a plurality of girth-fingers located upon each side of the machine and carried by horizontally-movable slides mounted upon a vertically-movable cross-head.

As the machine has been heretofore constructed girth-straps were attached at one end to the girth-fingers on one side of the machine and extended across the median line of the machine to its opposite side, passing through guides on the opposite girth-fingers and were connected with springs for holding them under tension. The two sets of girth-straps extending from the two sets of girth-fingers on the opposite sides of the machine crossed each other at the median line of the machine below the shoe to be lasted, which was supported at the heel and toe with its bottom uppermost, as is usual, and was secured against vertical displacement.

In the operation of the machine the cross-head supporting the finger-carrying slides was first raised, whereby the girth-straps attached to each set of girth-fingers were drawn upwardly across the median line of the machine and along the sides of the shoe, the springs to which the straps were connected yielding to allow this movement, and the upper of the shoe was thereby stretched simultaneously upon its two sides upwardly along the sides of the last. After the cross-head had been raised to a position where the girth-fingers were a short distance above the bottom of the last the finger-carrying slides were moved horizontally for carrying the girth-

fingers toward the median line of the machine and folding the upper over the edge of the last, the cross-head simultaneously descending to lower the girth-fingers to the level of the bottom of the last as they were moved inwardly, whereby the marginal portion of the upper was laid over on the bottom of the last in position to be secured by tacks to the inner sole. This horizontal movement of the finger-carrying slides was effected by means of levers, which were each connected at one end with a slide and at the other end were acted upon by a cam-plate, which was automatically operated to rock the lever for forcing the finger-carrying slide inwardly toward the median line of the machine.

In the use of the machine above referred to certain difficulties have been encountered in lasting shoes on what are known as "crooked" lasts. These lasts have a large amount of "swing" or projection on the outer side so that a greater portion of the width of the last bottom is on one side than on the other of the median line, extending from the center of the toe of the last to the center of the heel. Of course this excess of width is on the right side of a right last and on the left side of a left last, so that the right and left lasts are of very different shape. The lasting devices cannot be adjusted to conform to the shape of either a right or left last, because any adjustment required for one last is the reverse of that required for the other. When the girth-fingers are moved inwardly for overlaying the upper on the inner sole in the operation of lasting a shoe on a crooked last, the girth-straps on one side of the machine meet the edge of the wide side of the last before the girth-straps on the other side reach the edge of the narrow side of the last. One of the results of this is that the last, especially the toe end of it, is displaced laterally in the machine and put out of operative relation to the toe-lasting mechanism. Another result is that inasmuch as the last-supporting means resists the lateral displacement of the last and does not permit the last to be moved freely, the girth-fingers on the wide side begin to move over the last before those on the narrow side do, and so the girth-straps are carried over the bottom of the last a longer distance than they

should be on the wide side of the last and a less distance than they should be on the narrow side of the last, and frequently the upper is not drawn over the narrow side of the last 5 far enough to enable the workman to secure it properly on that side, while it is drawn over much farther than it should be on the wide side. To overcome this difficulty and enable the machine to last shoes properly on crooked 10 lasts is one of the objects of the present invention, and to this end I have provided the machine with means for causing the side-lasting mechanisms to adapt themselves automatically to the shape of the last presented 15 to the machine and to stretch the upper and lay it over on the bottom of the last equally on both sides irrespective of whether the last is a right or a left last.

The shape of the edge of the last is frequently 20 such that the fingers bearing the girth-straps, which extend under the fore part of the last, meet the edge of the last before the fingers bearing the girth-straps, which extend under the shank of the last. In order to permit 25 the girth-straps at the fore part and at the shank to come into bearing with the edge of the last equally, the machine is provided with one set of levers for actuating the girth-fingers carrying the girth-straps for the fore 30 part of the last and with another set of levers for actuating the girth-fingers carrying the girth-straps for the shank of the last and also with independently-movable cam-plates for actuating the levers of the shank-lasting devices and the levers of the fore part-lasting 35 devices. The machine is also provided with means for automatically returning the side-lasting mechanisms to their normal lateral positions, in which the girth-fingers on the 40 two sides are each spaced an equal distance from the median line of the machine.

In lasting-machines as heretofore constructed the girth-fingers have been so connected to their carrying-slides that they 45 could have no independent horizontal movement thereon. In practice the machine is used with one adjustment for lasting three sizes of shoes—as, for instance, 4's, 5's, and 6's—and a different adjustment is made for 50 the next three sizes. If the girth-fingers were properly adjusted for operating on a size-4 last and a size-6 last were put into the machine, they would sometimes strike the side of the last as the cross-head rose, and in 55 doing this they would bruise or mar the upper. This was particularly apt to occur if the large last was also unusually wide or unusually crooked. Another difficulty found was that inasmuch as the finger-carrying 60 slides were positively actuated inwardly said girth-fingers were unyieldingly moved over the bottom of the last always to the same innermost position, thus traveling a uniform distance at each operation of the machine 65 irrespective of the size of the last. It is de-

sirable to have the fingers moved inwardly over the edge of the last just far enough to fold the marginal edge portion of the upper over the edge of the last as the cross-head is lowered without drawing the girth-straps 70 across the edge of the last. If the machine is adjusted to give this extent of movement to the girth-fingers when a size-4 last is in position, it will obviously move the fingers a much greater distance inwardly from the 75 edge of the last when a wider last, such as a size 6, is in position.

In moving the girth-fingers farther than is necessary for merely folding over the marginal edge of the upper the girth-straps are 80 dragged across the upper at the angle where it is turned over the edge of the last, and in so doing tend to indent the upper and leave marks on it. Also if the inner sole is thin the girth-straps tend to crowd its edges inwardly 85 from the edge of the last and cause it to spring up away from the last in the middle. To overcome these difficulties, the girth-fingers of the present invention are so connected to the slides which carry them that 90 they may move horizontally thereon, and yielding means is provided for holding the fingers normally in their innermost positions. This arrangement permits the fingers to move away from the last without injuring the 95 upper if they contact with the side of the last in rising. This arrangement also permits the fingers which are properly adjusted for over-laying the upper on a small last to yield 100 backwardly in their carriers when being moved over a larger last and so travel over the bottom of the last only approximately the same distance from its edges as they travel over the smaller last, thus avoiding any tendency of the girth-straps to mark the upper or 105 to crowd the inner sole back from the edge of the last. This movable connection between the girth-fingers and the carrying-slides constitutes an important feature of this invention. 110

In the embodiment of the invention herein shown each girth-strap is attached at one end to one girth-finger and passes through guides on an opposing girth-finger and its carrying-slide in such a manner as to hold the two 115 girth-fingers yieldingly at the innermost limit of their movement on their carrying-slides. Of course other means might be employed, if desired, for holding the girth-fingers in their innermost positions and permitting them to yield when unusual resistance is encountered. 120

Figure 1 is a side elevation of a machine embodying the present invention. Fig. 2 is a plan view of the machine. Fig. 3 is a view, 125 partly in section, on approximately the plane of the dotted line 3 3 of Fig. 1. Fig. 4 is a detail view of the cross-head-actuating cam as seen from the plane of the dotted line 4 4 of Fig. 1. Fig. 5 is a section on the dotted 130

line 5 of Fig. 3. Fig. 6 is an enlarged sectional view on the dotted line 6 6 of Figs. 1 and 2, showing how the girth-straps encircle the last in folding the upper over onto the inner sole and also showing the movable connection between the girth-fingers and their carriers. Fig. 7 is a plan view of the side-lasting mechanisms, showing the positions assumed by the girth-fingers when lasting a right shoe. Fig. 8 is a view similar to Fig. 7, but showing the positions assumed by the girth-fingers when lasting a left shoe.

Referring to Figs. 1, 2, and 3 of the drawings, 1 indicates the base of the machine, said base being provided with bearings 22, in which is journaled the main shaft 3. Two pulleys 4 and 5 are loosely mounted on the main shaft, and these pulleys are continuously rotated in opposite directions by suitable means. (Not here shown.) The pulleys 4 and 5 are provided at their inner adjacent faces with suitable friction-surfaces adapted for engagement with the opposing friction-surfaces of disks or flanges 6 and 7, formed on the ends of a sliding sleeve 8, which is splined upon the main shaft 3 between said pulleys. The sliding sleeve is adapted to be shifted for putting either of the disks 6 or 7 into engagement with one of the continuously-rotating pulleys for the purpose of causing the main shaft to be rotated in one direction or the other at the will of the workman. For this purpose the sleeve is grooved circumferentially to receive a loose ring 9, which is provided with diametrically opposite trunnions 10 10. The trunnions are received in the forked arms of a yoke 11, which constitutes one arm of a rock-shaft 12, mounted in bearings on the base 1. The rock-shaft is provided with another arm 13, extended toward the front end of the machine and with a weight 13^a in position to counterbalance the arm 13 and cause the sleeve 8 to be held normally in an intermediate position with its friction-disks out of engagement with both of the pulleys 4 and 5. The arm 13 is provided with a foot-piece 13^x, by means of which said arm may be depressed and the rock-shaft turned in one direction. The arm 13 may be elevated for turning the rock-shaft in the opposite direction by means of a lifting-treadle 14, mounted in a bracket 15. For stopping rotation of the main shaft when the sliding sleeve 8 is moved into its intermediate position, said main shaft is provided with a brake-wheel 16, coöoperating with the brake-shoe 17, carried by an arm of a hub 18, which is fast on a shaft 19, mounted in bearings in posts 20 20 on the base 1, as shown most clearly in Fig. 2. The hub 18 is provided with another arm 21, having connection with one end of a spring 22, which acts normally to maintain the brake-shoe in holding contact with the brake-wheel. The shaft 19 is

provided with a pair of radially-extending arms 23 24, (see Fig. 2,) having at their ends adjustable stops 25, which lie directly over the ends of two laterally-extending arms 26 27 of the rock-shaft 12. When the rock-shaft 12 is turned in either direction to start the machine, one or the other of its arms 26 27 will be caused to turn the shaft 19 and remove the brake-shoe from the brake-wheel. When the rock-shaft 12 is returned to its normal position for allowing the main shaft to stop, the spring 22 reversely turns the shaft 19 and applies the brake to bring the main shaft to rest. A pinion 28 is fast on the front or left-hand end of the main shaft 3 (viewing Figs. 1 and 2) and meshes with a toothed wheel 29, fast on a shaft 30, which is journaled at one end in an extension 20^x of one of the posts 20 before referred to and at its other end in a suitable support. (Not shown.) The shaft 30 also has mounted upon it by means hereinafter described a pinion 31, (see Figs. 2 and 3,) which meshes with and drives a large toothed cam-wheel 32, fast on a shaft 33, which is journaled in stands 34^x 34^x in the base, as shown in Fig. 1

The cam-wheel 32 has formed on its left-hand face (see Fig. 4) a spiral cam-groove 34. On its opposite face the cam-wheel is provided with a spiral cam-groove 36. (Shown in Fig. 3.) A central column 37 is erected on the base 1, partially inclosing the cam-wheel 32, as most clearly shown in Fig. 1. The column carries at its top a table 38, and within the column is arranged in suitable guides 100 a vertically-sliding cross-head 39, which has depending from it an adjustable actuating-rod 40, forked at its lower end to straddle and be guided by the shaft 33, above mentioned. (See Figs. 1 and 4.) The actuating-rod 40 is provided on one side with a roller 41, which travels in the spiral cam-groove 34 in the cam-wheel 32, above described, whereby the rotation of said cam-wheel in one direction causes the cross-head 39 to be raised, and rotation in the opposite direction causes it to be lowered. The cross-head 39 carries upon its upper end at either side two slides 90 and 92.

The slides 90 support the lasting devices 115 which operate at the fore part of the last, and to this end they are grooved transversely, as shown most clearly in Fig. 6, to receive loosely blocks 91, which are socketed for the reception of stems 93 of finger-carriers 94, 120 which support girth-fingers 98. The stems of the finger-carriers may be clamped in the blocks 91 by means of set-screws 95 to hold the girth-fingers in any desired position, or said stems may be left free to turn in their sockets, so that the girth-fingers may automatically adjust themselves to the contour of the adjacent edge of the last to which they are presented. The girth-fingers are arranged in pairs opposite each other, and to 130

the inner free end of each finger is attached one end of a girth-strap 100, which extends from the finger across to the opposite side of the machine and through a guide-loop 102 on the opposite girth-finger. The outer free end of each girth-strap is secured to a spring 110, which holds the girth-strap always under tension.

The slides 92 support the lasting devices which operate at the shank of the shoe, and said slides are provided with sockets to receive the stems of the finger-carriers 114, in which are mounted girth-fingers 117. The stems may be clamped by screws 115 to hold the girth-fingers in any desired position. Girth-straps 118 are attached to the free ends of the girth-fingers 117 and extend inwardly and downwardly, their free ends being connected to springs 119 for holding them under tension.

The last having the upper, toe-stiffener, heel-stiffener, and inner sole thereon is supported upon an adjustable heel-post 120 and a toe-pad 122 in position immediately above the girth-straps and is held against upward movement by a downhold 128. The downhold is supported upon a cap-plate of the toe-lasting mechanism, being connected thereto by a pin-and-slot connection at 130, which permits the downhold to have a pivotal and also a longitudinal movement. The downhold has a lug or stud 128^x on one side, which is adapted to engage under a fixed projection 129 for fastening the downhold in its operative position after it has been turned down upon the shoe and then moved rearwardly. The spring 132 retains the downhold in position with the lug 128^x engaged under the projection 129, as shown in dotted lines in Fig. 1.

The toe-lasting mechanism, which will preferably be the same as that shown in United States Letters Patent No. 601,933, dated April 5, 1898, and therefore will not be described herein, is mounted for longitudinal adjustment upon the table 38 and comprises, among other parts, an abutment 100^x, against which the toe of the last may be positioned. The table 38 also supports a heel-lasting mechanism, which will preferably be the same as that shown in my pending application, Serial No. 686,319, filed July 19, 1898, said mechanism comprising among its parts a heel-band 157. The heel-lasting mechanism is movable longitudinally of the table by means of a hand-wheel 143 for clamping the last between the heel-band 157 and the abutment 100^x.

When the cross-head 39 is raised by the actuating-rod 40 and the spiral groove 34 in the cam-wheel 32, the slides and finger-carriers mounted on said cross-head will be likewise raised to cause the girth-fingers to draw the girth-straps tightly about the body of the last to stretch and conform the upper to the

shape of the last. The extent of the upward movement imparted to the cross-head is sufficient to carry the girth-fingers to a point somewhat above the level of the bottom of the last.

To prevent accident, which might occur if the main shaft 3 were not stopped promptly when the side-lasting devices had reached the limit of their movement, the pinion 31, before mentioned, is mounted upon a sleeve 31^a, loosely engaged about the shaft 30, (see Figs. 2 and 3,) and clutched to the latter by a suitable clutch, shown as comprising a disk 61, fast on the end of said sleeve 31^a and adapted to be engaged by a coöperating clutch member 62, which is splined upon the shaft 30. The clutch member 62 is grooved circumferentially to receive the end of a lever 63, (see Fig. 2,) which is fulcrumed at 64 and provided at its opposite end with a stud 85 running in contact with the face of the cam-disk 65, fast on the shaft 33. (See Fig. 1.) When the shaft 33 has rotated its proper distance, if the main shaft is not stopped by the workman, the cam 65 will disengage the clutch members 61 and 62 and stop the rotation of the shaft 33 and therefore stop the rotation of the cam-wheel 32, by which the side-lasting devices are actuated.

A slide-plate 140 is mounted within the cross-head 39 and is arranged to be reciprocated vertically in guideways 142 therein. The slide-plate supports a cam-plate, or, in the present instance, a plurality of cam-plates 150 and 170, (see Figs. 3 and 5,) from which the girth-fingers operating at the fore part and at the shank of the last, respectively, derive their horizontal movement, and said slide-plate is provided with a depending adjustable actuating-rod 144, which is forked at its lower end to straddle and be guided by the shaft 33, as shown in Fig. 3. The actuating-rod is provided with a roller-stud 146, standing in the spiral groove 36 in the cam-wheel 32, before described, so that said cam-wheel gives to said slide-plate a rising-and-falling movement. The cam-grooves 34 and 36 are so shaped that the slide-plate and the cross-head are moved together during the rise of the cross-head, and thereafter the slide-plate has a further upward movement, while the cross-head is slightly lowered by the portion 34^a of the cam-groove 34 (see Fig. 4,) for causing the girth-fingers to move the girth-straps for folding the upper over the edge of the last and laying it down upon the inner sole.

The cam-plate 150 is pivotally connected by a stud 152 to the upper end 154 of the slide-plate 140, above described, and is provided at either side near its lower end with guiding means, (shown as oppositely-inclined slots 156,) which receive studs 158 on the lower ends of levers 160. (See dotted lines in Fig. 5.) The levers 160 are fulcrumed on stud 162, project-

ing from the cross-head 39, and the upper ends of said levers extend through slots 164 in the upper end of the cross-head and are connected to the transversely-movable slides 90, upon which are mounted the finger-carriers 94, supporting the girth-fingers that operate at the fore part of the last. (See Fig. 6.) The second cam-plate 170 is pivotally connected to the stud 152 at the upper end 154 of the slide-plate 140 and is provided at either side near its lower end with guiding means, (shown as oppositely-inclined slots 176,) which receive studs 178 on the lower end of levers 180. The levers 180 are fulcrumed 15 on the studs 162, above referred to, and their upper ends extend through the slots 164 in the upper end of the cross-head and have connection with the transversely-movable slides 92, upon which are mounted the finger-carriers 114, supporting the girth-fingers that operate at the shank of the last. The movable cam-plate 170 and the levers 180 are similar to the movable cam-plate 150 and the levers 160.

25 The arrangement of the parts above described is such that when the slide-plate 140 and the cam-plates 150 and 170 are moved upwardly by the actuating-rod 144 and the spiral groove 36 in the cam-wheel 32 the levers 160 and 180 upon the opposite sides of the machine are rocked on their fulcrums for moving their upper ends inwardly toward the median line of the machine and moving the slides 90 and 92, together with the finger-carriers and girth-fingers, toward the median line of the machine for causing the girth-straps substantially to encircle the last and to fold the marginal portion of the upper over the bottom of the last.

30 While the girth-fingers are being moved inwardly by means of the levers 160 and 180 and the cam-plates 150 and 170 for laying the upper over the bottom of the last, the cross-head 39 is slightly lowered by the portion 34^a of the cam-groove 34, carrying down with it said girth-fingers, so as to bring the girth-fingers and the adjacent end portions of the girth-straps down upon the bottom of the last for laying the marginal portions of the upper down upon the inner sole in position to be secured thereto by tacks or other securing means. The inward movement of the girth-fingers and the downward movement of the cross-head and girth-fingers take place simultaneously, so that the ends of the girth-fingers to which the girths are attached describe a curve in folding the upper over upon the inner sole. When the girth-fingers are being closed or moved toward the median line of the machine by the cam-plates 150 and 170 acting through the levers 160 and 180, said fingers upon the opposite sides of the machine will move together toward the median line until the girth-straps on one side or the other meet the edge

of the last. If the last is a crooked right last, such as is shown in Fig. 7, it will be much wider on the left-hand side of its median line *a a* as the last is seen in the machine than on its right-hand side, and the girth-straps on the left-hand side of the machine will meet the edge of the last before the girth-straps on the right-hand side of the machine have reached the right-hand edge of the last. When the girth-straps on the left-hand side contact with the edge of the last, the cam-plates 150 and 170 will swing to the right on their pivots 152 and allow the fingers carrying those straps to remain at rest until the straps on the right-hand side have come into contact with the right-hand edge of the last, and thereafter said two sets of fingers will be actuated together to move the sets of straps over the bottom of the last for laying the upper down on the inner sole, and the fingers on each side will move over the last substantially the same distance.

35 If the last which is in the machine is a left last, such as is shown in Fig. 8, it will be wider on the right-hand side than upon the left-hand side, and the girth-straps on the right-hand side of the machine will meet the edge of the last before the straps on the left-hand side reach the left-hand edge of the last, and the cam-plates 150 and 170 will thereupon swing to the left upon their pivot, allowing the fingers at the right-hand side of the machine to remain at rest until the straps at the left-hand side of the machine have reached the edge of the last, and thereafter said two sets of fingers, with their girth-straps, will be moved inwardly together for the same distance. It will thus be seen that the provision of the swinging cam-plates 150 and 170 for moving the girth-fingers inwardly enables the fingers carrying those straps which first contact with the edge of the last to pause and remain at rest until the fingers carrying the straps at the opposite side of the last have also come into bearing with the edge of the last and that thereafter both sets of fingers are actuated together and caused to move over the last the same distance and that this action will take place automatically, whether the last is a right last or a left last and without regard to the degree of crookedness of the last. This construction entirely obviates the difficulties heretofore experienced in lasting shoes on crooked lasts with machines of this class in which the girth-fingers were positively moved together through the same distance and the girth-fingers or girth-straps which first contacted with the edge of the last tended to force the last laterally as they moved over it until such time as the fingers or straps on the opposite side came into bearing with the other edge of the last for supporting it against such lateral movement. Obviously, the fingers or straps at the opposite sides of the last moved over the bottom

of the last unequal distances, the fingers operating at the wide side of the last moving over it a much greater distance than the fingers operating on the narrow side of the last, and frequently the girth-fingers did not lay the upper over upon the narrow side of the last far enough to permit it to be secured to the inner sole.

- In the construction herein shown the slides 90 carrying the girth-fingers which operate upon the fore part of the last are actuated by the cam-plate 150 and levers 160, as above described, while the slides 92, carrying the girth-fingers which operate upon the shank of the last, are actuated by the independently movable cam-plate 170 and levers 180, as it is found that it is desirable to permit the fingers acting on the shank to move relatively to those acting on the fore part of the shoe, so as to enable said two sets of fingers to adapt themselves to the contour of the edge of the last. If desired, each of the fingers acting at the sides of the shoe might be mounted on an independent slide and actuated by an independent lever, so that said fingers might be permitted to move relatively when they met the edge of the last, and such a construction would be within the scope of the present invention.
- It will be understood that the cross-head is raised and the girth-fingers moved inwardly for lasting the shoe by a rotation of the main shaft in one direction and that the girth-fingers are moved outwardly and the cross-head is lowered, thus restoring the parts to their original positions by a rotation of the main shaft in the reverse direction.

The cross-head 39 is provided on its lower end at each side of the machine with lugs 190 in position to engage the movable cam-plates 150 and 170 when they are lowered into their starting positions. These lugs serve to shift the cam-plates laterally and restore them to their central normal position, in which position the girth-fingers upon the opposite sides of the machine are positioned the same distance from the median line of the machine.

The girth-fingers 98, operating at the fore part of the last, are mounted in guideways 50 formed by walls 191 on the finger-carriers, and said fingers are connected to the finger-carriers by means of a pin-and-slot connection comprising pins 192 and slots 194. This connection permits the girth-fingers to have 55 a horizontal movement in their guideways during the operation of the machine, this movement being independent of the movement of the slides 90. For the purpose of holding the fingers normally in their innermost position, as shown in Fig. 6, each girth-strap extends through a guide-loop 102 on the finger opposite to the one to which it is attached, and after passing through said guide-loop the strap passes downwardly and 60 inwardly over a roller 104, mounted on the

finger-carrier, and from thence upwardly over other rollers 106 and 108 on its way to the tension-spring 110, as clearly shown in Fig. 6. By this arrangement the girth-strap acts to hold the two opposite girth-fingers 70 yieldingly in their innermost positions while permitting said fingers to be moved outwardly. This construction is of advantage in that if the girth-fingers on either side of the shoe meet the side of the shoe when the cross-head is being raised they can yield outwardly until they have passed over the side of the shoe, and this is done without bruising or marring the upper, whereas if the fingers were rigidly connected to the finger-carriers they would scrape against the upper in such a case and injure it. Another advantage is that inasmuch as the fingers are not positively forced inwardly over the bottom of the last they will stop after having 80 moved far enough to fold the upper over the inner sole and will not draw the girth-straps across the angular edge of the last and indent the upper or force the inner sole away from the edge of the last.

In using the machine the shoe is put into place while the cross-head is in its lowermost position and the girth-fingers are spread apart, the heel-band being open. The heel-lasting mechanism is next advanced to bring the heel-band into engagement with the heel end of the last and clamp the last between the heel-band and the usual abutment on the toe-lasting mechanism. The machine is then started by depressing the foot-piece 13^x of the treadle-arm 13 of the rock-shaft 12 to put the friction-disk 6 into engagement with the pulley 4 and cause the main shaft to be started and the cam-wheel 32 to be rotated in the direction of the arrow thereon in Fig. 4. 95 This results in raising the cross-head by means of the cam-groove 34, acting on the actuating-rod 40. The rise of the cross-head continues until the portion 34^a of the cam-groove begins to act on the stud of the actuating-rod, after which the cross-head is slightly lowered. The slide-plate 140 moves upwardly in unison with the cross-head while the latter is rising and continues to rise during the short downward movement of the 105 cross-head. During this independent upward movement of the slide-plate and the cam-plates carried thereby the girth-fingers are moved inwardly to cause the girth-straps to fold the upper over the edge of the last. 110 The combined inward and downward movement of the girth-fingers causes the girth-straps to lay the marginal portion of the upper over upon the inner sole. If the workman fails to release the treadle-arm at the 115 right time, the cam 65 disengages the clutch members 61 62 and stops the machine at the time the lasting devices reach the limit of their movement. If the last is crooked, the girth-straps in moving inwardly meet the 120

125 130

edge of the last sooner on one side than on the other, and the cam-plates swing on their pivot, allowing the levers 160 and 180 actuating the girth-straps which first meet the last to pause, while those actuating the girth-straps at the opposite side of the last continue to move until those girth-straps also come into bearing with the edge of the last, after which the levers on both sides are moved together to cause the girth-straps to act uniformly on the two sides of the shoe. If the contour of the edge of the last is such that the girth-straps for lasting the fore part meet the last before those for lasting the shank, or vice versa, the girth-straps first meeting the edge of the last are stopped and wait until the other girth-straps on the same side come into bearing with the edge of the last. This causes the cam-plates 150 and 170 to move relatively until the two sets of girth-straps come into bearing equally with the edge of the last, and thereafter said cam-plates move together, so that the girth-straps of the fore part and of the shank act uniformly in folding the upper over the last. The sides of the shoe having been lasted, the heel and toe portions are lasted by their respective mechanisms, as is usual, and the workman secures the upper in lasted position by tacks. To return the side-lasting mechanism to its initial position, the workman operates the lifting-treadle 14 to turn the rock-shaft 12 for putting the disk 7 into engagement with the pulley 5, whereby the main shaft is turned in the reverse direction to that in which it was first turned. This causes the cam-wheel 32 to be turned backwardly or in the opposite direction to that indicated by the arrow in Fig. 4, whereby the slide-plate and the cam-plates 150 and 170 are first drawn downwardly for moving the girth-fingers outwardly, and then the cross-head, together with all the parts carried by it, is lowered to its initial position. As the slide-plate and the cam-plates are drawn downwardly the lower ends of the cam-plates engage the lugs 190 for restoring said cam-plates to their initial central positions with the lasting devices on each side spaced the same distance from the median line of the machine, so that they are prepared to act next either on a right shoe or a left shoe. If the girth-fingers meet the side of the last when the cross-head is being raised or lowered, they will yield outwardly without injuring the upper of the shoe. If a shoe is being lasted which is larger or wider than the size of shoes for which the machine has been adjusted, the girth-fingers will yield backwardly in their carrying-slides after having moved over the last only approximately the same distance as they would have moved over the smaller last for which they were adjusted.

Having thus described my invention, what

I claim as new, and desire to secure by Letters Patent in the United States, is—

1. In a machine of the class described, straps for encircling the last and folding the edges of the upper over the last upon its opposite sides, in combination with means for automatically causing the straps to act uniformly on the shoe at the two sides of the last. 70

2. In a machine of the class described, side-lasting mechanism comprising girth-fingers, girth-straps, and means for actuating said girth-fingers to cause the girth-straps to encircle the last, said actuating mechanism having provision for automatically causing the girth-straps to act uniformly on the shoe at the opposite sides of the last. 80

3. In a machine for lasting shoes, side-lasting mechanisms arranged at opposite sides of the machine, each mechanism comprising girth-straps for lasting the fore part and girth-straps for lasting the shank, in combination with actuating mechanism for causing the two side-lasting mechanisms to act uniformly upon the opposite sides of the shoe, said actuating mechanism comprising independent operating means for the fore-part girth-straps and the shank girth-straps arranged to permit said girth-straps to position themselves relatively according to the contour of the side of the last. 90

4. In a machine of the class described, the combination with side-lasting devices for operating at the sides of a shoe, of actuating mechanism therefor comprising a reciprocating slide-plate, a cam-plate pivotally mounted on said slide-plate, and means connected with the side-lasting devices and controlled by said cam-plate for moving the side-lasting devices positively toward and from the shoe. 100

5. In a machine of the class described, the combination with side-lasting mechanisms for operating upon opposite sides of a shoe, of actuating mechanism therefor comprising a reciprocating slide-plate, a cam-plate pivotally mounted on said slide-plate and provided with oppositely-inclined slots, levers having rolls standing in said slots and connected at their opposite ends with the side-lasting mechanisms, whereby as the slide-plate is moved in one direction the levers will force the side-lasting mechanisms toward each other until one of said mechanisms contacts with the edge of the shoe, and then said cam-plate will turn on its pivot until the other side-lasting mechanism reaches the edge of the shoe toward which it is moving, after which said two lasting mechanisms will be moved together for equal distances over the bottom of the shoe. 115

6. In a machine of the class described, the combination with side-lasting devices for operating upon the sides of a shoe, of actuating mechanism therefor comprising a reciprocating slide-plate, a cam-plate provided 125

130

with oppositely-inclined slots, levers controlled by said slots and connected with said lasting mechanisms for moving said mechanisms positively back and forth, and a movable connection between the slide-plate and the cam-plate whereby the side-lasting mechanisms may be moved together until one of them contacts with the edge of the last and is brought to rest and the other side-lasting mechanism will continue to move until it also contacts with the edge of the last, after which both mechanisms will be actuated together to lay the upper over the inner sole.

15 7. In a machine of the class described, the combination with side-lasting mechanisms for operating upon opposite sides of a shoe, of actuating mechanism therefor comprising a vertically-movable cross-head supporting 20 said lasting mechanisms, means to actuate the cross-head, a slide-plate movably mounted in the cross-head, a cam-plate carried by the slide-plate and provided with guiding means, levers controlled by said guiding 25 means and connected to said lasting mechanisms for moving them horizontally, means for actuating the said plate independently of the cross-head, and a pivotal connection between the cam-plate and the slide-plate 30 to permit a relative movement between said plates for equalizing the pressure applied to the two side-lasting mechanisms.

8. In a machine of the class described, the combination with side-lasting mechanisms 35 for operating upon opposite sides of a shoe, each lasting mechanism comprising independently-movable lasting devices, of actuating mechanism comprising a plurality of cam-plates and means connected with said 40 lasting devices and controlled by the cam-plates for operating the lasting devices, said cam-plates being relatively movable whereby the lasting devices are independently actuated and permitted to have relative movement.

45 9. In a machine of the class described, the combination with side-lasting mechanisms for operating upon opposite sides of a shoe, each lasting mechanism comprising independently-movable lasting devices arranged 50 along the same side of the shoe, of actuating mechanism comprising a plurality of cam-plates and means connected with said lasting devices and controlled by the cam-plates for operating the lasting devices, said cam-plates being relatively movable whereby the lasting devices on the same side of the shoe 55 are independently actuated and permitted to have relative movement.

60 10. In a machine of the class described, side-lasting devices for operating upon the opposite sides of the fore part of a shoe, actuating mechanism therefor comprising a reciprocating slide-plate, a cam-plate pivotally 65 mounted on said slide-plate, and means con-

nected with said side-lasting mechanisms and controlled by said cam-plate for moving the side-lasting devices toward and from the fore part of the shoe, in combination with lasting devices for operating on the opposite 70 sides of the shank of the shoe, and actuating mechanism therefor comprising a cam-plate pivotally mounted on said slide-plate, and means connected with said shank-lasting mechanisms and controlled by said cam-plate for moving said mechanisms toward 75 and from the shank of the shoe.

11. In a machine of the class described, the combination with side-lasting devices for operating on opposite sides of the shoe, of actuating mechanism therefor, comprising a slide-plate, a cam-plate, means connected 80 with said lasting mechanisms and controlled by said cam-plate for operating the lasting mechanisms to lay the upper over the inner 85 sole when the slide-plate is moved in one direction, said cam-plate being movably connected to the slide-plate whereby the side-lasting mechanisms may be operated through different distances, and means for restoring 90 said cam-plate to normal central position when the slide-plate is moved in the reverse direction.

12. In a machine of the class described, side-lasting mechanism comprising a finger-carrier, a girth-finger, and a pivotal connection between the carrier and the finger, said 95 parts being constructed and arranged to permit longitudinal movement of the girth-finger relatively to its carrier during the normal 100 operation of the machine.

13. In a machine of the class described, side-lasting mechanisms for operating upon opposite sides of a shoe, said mechanisms comprising girth-fingers, girth-straps attached thereto, carriers pivotally supporting said girth-fingers, said fingers and carriers being constructed and arranged to permit longitudinal movement of the girth-fingers 105 relatively to the carriers, and means for actuating said carriers to move the girth-fingers yieldingly toward the median line of the machine, said mechanisms having provision for allowing the girth-fingers to be arrested by excessive resistance while the actuating 110 means and carriers continue to move.

14. In a machine of the class described, side-lasting mechanisms for operating upon opposite sides of a shoe, said mechanisms comprising opposing girth-fingers, carriers 115 upon which the girth-fingers are mounted for longitudinal movement during the operation of the machine, a girth-strap connecting said opposing girth-fingers, and yielding means acting on said girth-strap for drawing said 120 girth-fingers normally toward each other.

15. In a machine of the class described, side-lasting mechanism comprising a finger-carrier, a girth-finger, a pivotal connection between said finger and finger-carrier, said 125 130

parts being constructed and arranged to permit longitudinal movement of the finger relatively to the carrier during the operation of the machine, and yielding means for holding the girth-finger normally at one limit of its longitudinal movement.

16. In a machine of the class described, side-lasting mechanism comprising a finger-carrier provided with a longitudinal guideway, a finger mounted in said guideway, a pivotal connection between the finger and the finger-carrier, said carrier and finger being constructed and arranged to permit longitudinal movement of the finger in said guideway during the normal operation of the machine.

17. In a machine of the class described, side-lasting mechanisms for operating upon opposite sides of a shoe, each of said mechanisms comprising a finger-carrier, a girth-finger longitudinally movable thereon, guiding devices on the girth-finger and the finger-carrier and a girth-strap connected at one end to said girth-finger and threaded through guiding devices on a girth-finger and its carrier of the opposite side-lasting mechanism, yielding means for holding each girth-finger

at the innermost limit of its movement, and means for moving said lasting mechanisms vertically with relation to the last for stretching the upper along the sides of the last.

18. In a machine of the class described, side-lasting mechanisms for operating upon opposite sides of a shoe, each of said mechanisms comprising a finger-carrier, a girth-finger longitudinally movable thereon, guiding devices on the girth-finger and the finger-carrier and a girth-strap connected at one end to said girth-finger and threaded through guiding devices on the girth-finger and its carrier of the opposite side-lasting mechanism, and yielding means for holding said girth-strap under tension, said guiding devices being so arranged that the girth-strap holds the opposing girth-fingers at the innermost limit of their movement on their carriers.

In testimony whereof I have signed my name to this specification in the presence of two subscribing witnesses.
